Primary Examiner—Catherine R. Oliver

(57) **CLAIM**

The ornamental design for a leg pocket, as shown and described.

DESCRIPTION

FIG. 1 is a front perspective view of a leg pocket showing my new design;

FIG. 2 is a rear elevational view thereof;

FIG. 3 is a side elevational view thereof;

FIG. 4 is a front elevational view; and,

FIG. 5 is a top plan view.

The broken line showing of environment in the drawings is for illustrative purposes only and forms no part of the claimed design.
